UNITED STATES PATENT OFFICE.

EDWARD ALLEN RASHELL, OF LAMASCO, TEXAS, ASSIGNOR OF ONE-HALF TO W. L. SMART, OF LAMASCO, TEXAS.

MAIL-TRANSFERRING APPARATUS.

1,337,956.

Specification of Letters Patent.

Patented Apr. 20, 1920.

Application filed March 20, 1918. Serial No. 223,582.

To all whom it may concern:

Be it known that I, EDWARD A. RASHELL, a citizen of the United States, residing at Lamasco, in the county of Fannin and State 5 of Texas, have invented certain new and useful Improvements in Mail-Transferring Apparatus, of which the following is a specification.

This invention relates to mail transfer 10 ring apparatus and more particularly to an improved construction whereby mail sacks may be readily transferred from a station to a moving mail car without injury being done to the mail sack or to the contents 15 thereof.

One of the principal objects of the invention is to provide a mail bag transferring apparatus including a bag or sack holder adapted to tightly hold the mail bag when 20 filled with mail and also designed to be readily caught by a receiving device on the moving mail car whereby the mail sack may be transferred from a stationary point at the side of the railway to the mail car and 25 be swung into the latter in a manner that will reduce to a minimum the danger of injuring the employees in the mail car.

A further object of this invention is to provide a device of this character which 30 consists of comparatively few parts and is simple in construction but durable and well adapted to withstand the rough usage to which devices of this character are ordinarily subjected.

35 For a full description of the invention and the advantages and merits thereof, reference is to be had to the following description and accompanying drawings wherein:—

40 Figure 1 is a top plan view of the device constructed in accordance with my invention.

Fig. 2 is a side elevation of the bag holding portion of the invention.

45 Fig. 3 is a detail section through a portion of the apparatus.

Referring to the drawings, wherein is illustrated the preferred form of my invention, in which like numerals of reference 50 indicate corresponding parts throughout the several views, the side wall A of the mail car is provided with the usual doorway B through which the mail is received. Arranged within the car is a shaft 1 supported 55 in suitable bearings 2 which are preferably

attached to the hanger members 3 suspended from a portion of the roof of the car. Rotatably mounted upon the shaft 1 is a sleeve 4 and this sleeve carries a hand lever 5 adapted to be grasped by the operator when 60 the sleeve 4 is to be operated on the shaft 1. A suitable spring-pressed locking-pin 6 is extended through an opening in the sleeve 4 and is pivotally connected to a thumb lever associated with the hand lever 5 for 65 the purpose of actuating the locking pin when the lever is gripped in the manner common to the well known locking devices of this type. The end of the locking pin 6 is received in an elongated groove or key 70 way 7 shown to advantage in Fig. 3, of the drawing. Thus when the locking pin 6 is released from the groove or key way 7 the sleeve may be readily rotated on the shaft 1.

Projecting from the sleeve 4 at a point 75 diametrically opposite the lever 5 is an extension 8, the end of which is integrally connected with an enlarged hook 9 which is adapted to be disposed in a position for readily engaging the mail sacks mounted at 80 the sides of the railway at a transferring station.

By referring to Fig. 1 of the drawing it will be observed that the bight 10 of the hook is in close proximity to one edge of 85 the door-way of the mail car, while the bill 11 is of straight formation and terminates at a point near the opposite edge of the door-way. In other words the bight of the hook is in close proximity to one edge of the 90 door-way while the terminal of the bill of the hook is slightly spaced from the opposite edge of the door for a purpose that will presently appear.

The mail sack C is attached to the sack 95 holder which includes the straight bar 12 provided with loops 13 at opposite sides and longitudinally spaced apart for receiving the ends of fastening straps 14 which extend around the mail sack and tightly hold 100 the latter to the bar 12. Obviously, each of these straps 14 may be provided with a buckle to tighten the sacks to the bar 12 if the sack is only partially filled with mail. Attached to the bar 12 is a bow 15 which consists of a steel rod of substantially hemispherical formation. The ends of the rod 105 are attached to the bar 12 and this bow is also bridged by the brace member 16 which acts to prevent disconnection of the bow 110

from the bar 12 during the mail transferring operation.

The mail bag may be suspended at the side of the railway station and any number may be arranged in a row, all of course, being provided with a sack holder. In the present instance, the mail bag is provided with a suitable eyelet 17 adapted to receive one end of a supporting hook 18 which latter may be supported by any suitable device such as a rafter projecting from the station. While supported as shown in Fig. 2 of the drawing, it will be obvious that the portion 11 of the mail hook carried by the car will be extended through the bow 15 and when the hook is passed forwardly until the portion 10 engages the bow it will be obvious that the bag will be removed from the hook 18. Instead of swinging into the car, however, the bag will be thrown against the exterior of the car by virtue of the close proximity of the portion 10 to the edge of the door-way. The bow 15, however, being of semi-circular formation will permit the bag to swing to a horizontal position so that the bag will be supported by the bow from the hook at a point indicated at 19. It will then be an easy matter for the employee within the mail car to slide the bag toward the end of the hook and pass it over the end thereof whereby it may be drawn into the car if the hook is to remain in operative position. This method of removing the mail sack, however, is not necessary for the reason that the hand lever 5 may be actuated for the purpose of swinging the sleeve 4 on the shaft 1 thus permitting the hook to swing downwardly into the car whereupon the mail bag carried by the hook will be readily removed by sliding the bow over the end of the portion 11 which will then be disposed within the car.

The device is especially adapted for preventing injury being done to the contents of the bag or to the bag itself as it will be readily seen that when the hook engages the bow 15 the bar 12 will prevent contact of the end of the hook with the bag and also the strap 14 snugly engaging the bag will

be of heavy material and will prevent the bag or the contents thereof being injured when the bag is swung against the exterior of the car. In addition to its use for protecting the bag, the holder is especially adapted for use with this particular type of hook element as has been set forth.

From the foregoing it will be observed that a very simple and durable transferring device has been provided, the details of which embody the preferred form. I desire it to be understood, that slight changes may be made in the minor details of construction, without departing from the spirit of the invention or the scope of the claim hereunto appended.

65
I claim:

An apparatus of the character described adapted for use on a railway car, comprising a horizontal support mounted within the car, a sleeve member slidably mounted on the support means mounted on the sleeve member to normally lock the said sleeve against rotary movement on the horizontal support and adapted to be released whereby the said sleeve may be turned on the support, the said horizontal support being in such proximity to the doorway of the said car as to permit the approximate closing of door, and a hook member carried by the said sleeve and comprising a lateral extension having the bight portion of the said hook connected thereto, the bill of the hook being less than the width of the car door way, whereby the said hook may be projected through the said doorway when the said sleeve is swung on the horizontal support, the said releasable means being adapted to maintain the sleeve in position against rotation whereby the said end of the hook may be held in a horizontal position on the exterior of the car.
